Atty.

UNITED STATES PATENT OFFICE.

IRA R. SELTZER, OF WATERBURY, CONNECTICUT, ASSIGNOR TO THE GORDON ELECTRIC MFG. CO., OF WATERVILLE, CONNECTICUT, A CORPORATION.

INCANDESCENT-LAMP SOCKET.

Application filed May 7, 1921. Serial No. 497,760.

To all whom it may concern:

Be it known that I, IRA R. SELTZER, a citizen of the United States, residing at Waterbury, in the county of New Haven 5 and State of Connecticut, have invented a new and useful Improvement in Incandescent-Lamp Sockets; and I do hereby declare the following, when taken in connection with the accompanying drawings and 10 the characters of reference marked thereon, to be a full, clear, and exact description of the same, and which said drawings constitute part of this application, and represent in—

Fig. 1 a view in side elevation of a lamp-socket body embodying my invention.

Fig. 2 a plan view thereof.

Fig. 3 a view thereof in vertical section on the line 3—3 of Fig. 2.

Fig. 4 a view thereof in elevation, with the body turned a half turn from the position in which it is shown in Fig. 1.

Fig. 5 a reverse plan view thereof.

Fig. 6 a plan view of the body showing the application thereto of the two terminal-plates and the contact-spring.

Fig. 7 a view in vertical section of the assembled socket.

Fig. 8 a reverse plan view thereof.

My invention relates to an improved incandescent lamp-socket, the object being to produce a simple, compact and efficient socket constructed with particular reference to protecting the wires from abrasion and 35 injury.

With these ends in view, my invention consists in an incandescent lamp-socket having certain details of construction as will be hereinafter described and pointed out 40 in the claims.

In carrying out my invention, as herein shown, I employ a socket-body 4 made of porcelain or any molded suitable insulating composition, and provided at the time of 45 being molded with an internally threaded coupling-sleeve 5 having an embedded anchoring-flange 6 and adapting the socket-body to be applied to the outlet pipe through which the wires are led. The 50 socket-body is also provided, at the time of being molded, with a centrally depending eyelet 7 and two depending eyelets 8 arranged on opposite sides thereof. The coupling-sleeve 5 opens directly at its in-

ner end into an internal concentric passage 55 9 from which two smaller, corresponding passages 10 lead in opposite directions into deep lateral recesses 11 formed at opposite points in the periphery of the body, the said passages 9 and 10 and the recesses 11 60 being formed in the body at the time of molding the same to permit the wires 12 and 13 to be led directly through the interior of the body.

The central eyelet 7 is employed for the 65 attachment of a terminal plate 14 and a spring contact-finger 15, as clearly shown in Fig. 7, the plate 14 carrying a binding-screw 16. The lateral eyelets 8 are employed for the attachment to the body, as shown 70 in Figs. 6 and 7, of a yoke-shaped terminal-plate 17 and a screw-shell 18, the former being provided as usual with a binding-screw 19. After the parts have been assembled they are enclosed by an insulating shell 20 75 fitting over the screw-shell 18 and abutting against a shoulder 21 molded in the body 4.

It will be seen by particular reference to Fig. 7 that the wires 12 and 13 instead of being led around on the outside of the 80 body, are passed directly through the coupling-sleeve 5 into the interior of the body where they are connected with the respective binding-screws of the terminal-plate at points so far within the periphery of the 85 body that they are entirely protected against those abrasions which occur when the wires are led around on the outside of the body and let into shallow peripheral notches 90 therein as in the sockets of the prior art.

I claim:

1. In an incandescent lamp-socket, the combination with a molded body formed with internally-arranged passages for the current-receiving wires, of an internally- 95 threaded coupling-sleeve anchored in the said body when the same is molded, and having its inner end open to communicate with the passages thereof, terminal plates and a spring-contact applied to the body 100 within the periphery thereof, and an insulating shell applied over the body, whereby the current-carrying wires are located within the periphery of the body and their abrasion prevented.

2. In an incandescent lamp-socket, the combination with a molded body formed with a concentric main passage, two sec-

ondary passages leading in opposite directions therefrom and two deep recesses formed in the periphery of the body and respectively communicating with the said secondary passages; of an internally-threaded coupling-sleeve anchored in the said body when the same is molded and open at its inner end to communicate with the concentric main passage thereof, terminal plates and 10 a spring-contact located within the said body, and an insulating shell applied over the body.

3. In an incandescent lamp-socket, the combination with a molded body formed 15 with internally-arranged passages, of a coupling-sleeve anchored in the said body and having its inner end open to communicate with the said passages, central and lateral eyelets molded into the said body, a terminal-plate and a spring-contact applied to the 20 said central eyelet, a terminal-plate and a screw-shell applied to the said lateral eye-

lets, and an insulating shell applied over the said body and screw-shell.

4. In an incandescent lamp-socket, the 25 combination with a molded body made of insulating material and formed with internally-arranged passages, of an internally-threaded coupling-sleeve molded into the said body and having its inner end open 30 to communicate with the said passages, central and lateral eyelets molded into the body, a terminal-plate and a spring-contact applied to the central eyelet, a yoke-shaped terminal-plate and a threaded shell applied 35 to the lateral eyelets, and an insulating shell applied over the said body.

In testimony whereof, I have signed this specification in the presence of two subscribing witnesses.

IRA R. SELTZER.
